UNITED STATES PATENT OFFICE.

SAMUEL M. KIRSHNER, OF PHILADELPHIA, PENNSYLVANIA.

INSTALLING DEVICE FOR PLACING REINFORCING IN CONCRETE.

Application filed May 25, 1927. Serial No. 193,995.

My invention relates to a new and useful installing device for placing reenforcing in concrete, and more particularly to a supporting and spacing device whereby the reenforcing wire mesh or "bar mat" may be supported in position with respect to the road bed while the concrete is being poured, to insure uniform level and proper spacing of the reenforcing material.

10 My invention further relates to an installing device whereby a plurality of vertically spaced layers or "lines" of reenforcing wire mesh, or the like, may be supported in a mold or form while the concrete is poured, 15 one layer of reenforcing wire mesh being near the bottom and one near the top of such mold, as may be desired.

To the above ends, my invention consists of a yoke or transverse supporting beam 20 adapted to be supported by the upper edges of the walls of a mold or form into which concrete is to be poured, a plurality of pendant arms or hooks rigidly secured to said yoke at suitable intervals, said pendant arms 25 being provided with vertically spaced and horizontally projecting lugs adapted to engage and support the transverse wires or bars of a reenforcing wire mesh or "bar mat", locking pins adapted to engage the apertures in 30 said lugs, and a handle on the end of said yoke whereby the same may be revolved or turned to withdraw said pendant arms from engagement with the reenforcing wire mesh after the concrete has been poured.

35 My invention further consists in the novel features and details of construction illustrated in the accompanying drawings and described in the annexed specification.

For the purpose of illustrating my invention, I have shown, in the accompanying drawings, a form thereof which is at present preferred by me since it will give, in practice, satisfactory and reliable results, although it is to be understood that the various instrumentalities of which my invention consists can be variously arranged and organized and that my invention is not limited to the precise arrangement and organization of these instrumentalities as 45 herein shown and described.

In the accompanying drawings:

Fig. 1 represents a top plan view of the installing device embodying my invention.

Fig. 2 represents a side elevation of the same, certain parts being shown in section. 55

Fig. 3 represents an end view on line 3—3 of Fig. 2.

Fig. 4 represents a reenforcing mat of steel bars or wire mesh.

Fig. 5 represents a view on line 5—5 Fig. 2. 60

Referring to the drawings, in which like reference characters indicate like parts, 1 designates the road bed or sub-grade of a street or the like, on the sides of which are positioned the suitably spaced construction 65 walls or mold sections 2 between which the concrete is to be poured and which support the transversely disposed supporting beam or yoke 3, from which depend the supporting arms or hooks 4, rigidly secured thereto by 70 the bolts or rivets 5. 6 and 6^x designate upper and lower horizontally projecting apertured lugs or hooks which are adapted to support the transverse wires 7 of the reenforcing mat of bars or wire mesh 8 or the 75 like, shown in Fig. 4. A locking pin 9, having the upper handle 10, is adapted to be inserted through the vertically aligning apertures 11 in said lugs 6 and 6^x, to prevent displacement of the transverse wires 7 of the 80 wire mesh 8 with respect to said lugs, thereby to maintain the wire mesh 8 in position while the concrete is being poured in the mold. A handle 12 is rigidly secured to either or both 85 ends of the yoke or beam 3 by means of the bolts or rivets 13, whereby said yoke may be turned or revolved to withdraw the pendant arms from engagement with the wire mesh 8 after the concrete has been poured.

The beam or yoke 3 is further provided with the pendant supporting arms 15, rigidly secured thereto by the bolts or rivets 5, and having the outwardly projecting lugs 16 and 17 which support the transverse wires 7 of the wire mesh 8 or the like, in the manner shown 95 in Figs. 1, 2 and 5, the purpose of said arms 15 being merely to support the body of the wire mesh 8 against sagging until the concrete has been poured, two or three arms 4 having locking pins 9 coating therewith being sufficient 100 to prevent the displacement of the wire mesh 8, although it is to be understood that the number of arms 4 and 15, as well as the number and character of the lugs 6 and 6^x and 16 and 17 may be varied to suit varying requirements, the particular number and character of 105

such arms and lugs shown in the drawings being merely illustrative of the invention.

Thus, for instance, when it is desired to build a concrete road having, say, a double line or layer of reenforcing wire mesh, that is, one layer of reenforcing wire mesh near the bottom, and one near the top thereof, the sub-grade 1 is first laid out and levelled, and the mold sections or construction walls 2 are 10 erected on either side thereof to form mold or form in which the concrete may be poured, as will be understood from Fig. 2. The beam or yoke 3 is then supported transversely of the road bed, on the upper edges of the mold 15 sections 2, with the pendant arms 4 and 15 extending downwardly into the mold. The reenforcing mats of steel bars or wire mesh 8 are then supported on the suitably spaced upper and lower apertured lugs 6 and 6*, and 20 the lugs 16 and 17, of the pendant arms or hooks 4 and 15 respectively, with the locking pins 9 passing through the apertures 11 in the lugs 6 6* to prevent the displacement of said wire mesh. After the concrete has been 25 poured to the desired height, the locking pins 9 are withdrawn from their engaging position, and the beam 3 is turned or revolved in the direction of the arrows 14, by the handle 12, through an angle of 90 degrees, so that said 30 handle 12 and said arms 4 and 15 occupy the position shown dotted in Fig. 3. In this position, the arms 4 and 15 are withdrawn from engagement with the wire mesh 8 which is now suspended in the concrete. To permit 35 of the withdrawal of the arms 4 and 15 from engagement with the wire mesh 8 in the manner just described, after the concrete has been poured, the arms 4 and 15 are made shorter than the distance between any two successive 40 wires of the reenforcing wire mesh. The beam or yoke 3 is then advanced or moved to new position and revolved in the reverse direction so that the arms 4 and 15 are again in the position shown in Figs. 1 and 2, and 45 the operation is again repeated.

While in the foregoing description and in the accompanying drawings, I have disclosed pendant arms or hooks 4 and 15 having two vertically spaced outwardly projecting lugs 50 for the support of two corresponding, vertically spaced, layers of wire mesh or the like, it is to be understood that it is within the scope of my invention to vary the number of said arms and lugs to suit varying requirements, the particular arrangement shown and described being merely for the purpose of illustration.

It will thus be apparent that I have devised a new and useful installing device for placing 60 reenforcing in concrete, which embodies the features of advantage enumerated as desirable in the statement of the invention and the above description and while I have, in the accompanying specification shown and described a preferred embodiment thereof, it is

to be understood that such embodiment is susceptible of modification in various particulars without departing from the spirit or scope of the invention, or sacrificing any of its advantages.

Having thus described my invention, what I claim as new and desire to secure by Letters Patent is:

1. In a device of the character stated, a yoke, pendant hooks supported therefrom, 75 arms extending laterally from said hooks, certain of said arms having aligning holes therein, upright pins positioned in said holes, and a laterally extending handle projecting from said yoke, whereby said yoke and hooks 80 may be revolved as a unit.

2. In a device of the character stated, a mold for the reception of concrete, a yoke supported thereon, a plurality of pendant arms rigidly secured to said yoke and having outwardly 85 projecting apertured lugs adapted to engage and support reenforcing fabric, locking pins engaging the apertures in said lugs to prevent the displacement of said reenforcing fabric while the concrete is being poured, and a handle for said yoke, whereby the latter may be actuated with respect to said mold to withdraw said pendant from engagement with said reenforcing fabric after the concrete has 90 been poured.

3. In a device of the character stated, a mold for the reception of concrete, a yoke supported thereon, a plurality of pendant arms rigidly secured to said yoke and having outwardly projecting apertured lugs adapted to 100 engage and support the transverse wires of a reenforcing wire mesh, locking pins engaging the apertures in said lugs to prevent the displacement of said reenforcing wire mesh, while the concrete is being poured, and a handle for said yoke, whereby the latter may be moved with respect to said mold to withdraw said pendant arms from engagement with said reenforcing wire mesh after the concrete has 105 been poured.

4. In a device of the character stated, a mold for the reception of concrete, a yoke supported thereon, a plurality of spaced pendant arms rigidly secured to said yoke and having outwardly projecting apertured lugs adapted 115 to engage the transverse wires of the reenforcing wire mesh, locking pins engaging the apertures in said lugs to prevent the displacement of said reenforcing wire mesh, a plurality of pendant arms rigidly secured to 120 said yoke and having outwardly projecting lugs adapted to support said reenforcing wire mesh in position, and a handle for said yoke whereby the same may be actuated to withdraw said pendant arms from engagement with said reenforcing wire mesh in said mold after the concrete has been poured, the length of said pendant arms being less than the distance between any two successive transverse 125 wires of said reenforcing wire mesh.

5. In a device of the character stated, a mold for the reception of concrete, a yoke transversely supported thereon, a plurality of vertically spaced, outwardly projecting, apertured lugs, adapted to engage the transverse wires of corresponding, vertically spaced, layers of reenforcing wire mesh, locking pins engaging the apertures in said lugs to prevent the displacement of said reenforcing layers, 10 a plurality of spaced pendant arms carried by said yoke and having vertically spaced outwardly projecting lugs adapted to support said reenforcing layers and a handle for said yoke whereby the same may be revolved to withdraw said pendant arms from engagement with said reenforcing layers in said mold after the concrete has been poured, the length of said pendant arms being less than the distance between any two successive transverse wires of said reenforcing wire mesh. 15 6. In a device of the character stated, a mold for the reception of concrete, a transverse yoke supported thereon, a plurality of spaced arms rigidly secured to said yoke and adapted to extend downwardly into said mold, each of 20 said arms being provided with a plurality of vertically spaced, horizontally projecting, apertured lugs of varying lengths adapted to support the transverse wires of a reenforcing fabric, locking pins engaging the apertures 25 in said lugs to prevent the displacement of said fabric, handles on the outer ends of said pins, a plurality of pendant arms rigidly secured to said yoke and adapted to extend into said mold, each of said arms having a plurality of vertically spaced, outwardly projecting, lugs adapted to support said reenforcing fabric in position while the concrete is being poured, and handles on either end of 30 said yoke whereby the same may be revolved to withdraw said pendant arms from engagement with said reenforcing fabric, the length of said pendant arms being less than the distance between the wires of said reenforcing fabric. 35

SAMUEL M. KIRSHNER.
